UNITED STATES PATENT OFFICE.

CHARLES F. SPARKS, OF ALTON, ILLINOIS.

STEAM-ENGINE.

SPECIFICATION forming part of Letters Patent No. 586,877, dated July 20, 1897.

Application filed February 10, 1896. Serial No. 578,697. (No model.)

To all whom it may concern:

Be it known that I, CHARLES F. SPARKS, a citizen of the United States, residing at Alton, in the county of Madison and State of Illinois, have invented a new and useful Improvement 5 in Steam-Engines, of which the following is a specification.

My invention relates, chiefly, to improvements in engines in which a rotary movement is imparted to the main shaft by the longitudinal movements of a plurality of pistons; and the objects of my improvement are, first, to produce an engine which will be simple and durable and not liable to get out of order; second, to reduce friction; third, to provide an improved cut-off valve and governor, and, fourth, to combine said valve and governor with an engine of the class above mentioned. I attain these objects by mechanism 20 illustrated in the accompanying drawings, in which—

Figure 1 is a vertical longitudinal section on line 1 1, Fig. 2. Fig. 2 is a vertical cross-section on line 2 2, Fig. 1. Fig. 3 is a vertical cross-section on line 3 3, Fig. 1. Fig. 4 is a vertical section of a detail on line 4 4, Fig. 3. Fig. 5 is a vertical cross-section on line 5 5, Fig. 1, looking inward. Fig. 6 is a vertical cross-section on line 6 6, Fig. 1, looking inward. Fig. 7 is a section of a detail on line 7 7, Fig. 6; and Fig. 8 is a detailed view in elevation of a modification of the cut-off mechanism represented in other figures.

Similar letters refer to similar parts throughout the several views.

A represents a cylinder-casting having formed therein a series of cylinders a' , a^2 , a^3 , and a^4 .

The cylinders are preferably four in number, but any number from two up may be used. They are preferably regularly arranged around the shaft hereinafter mentioned at equal distances therefrom and with their axes parallel with the axis of the shaft.

Each cylinder is provided with a piston a^5 , whose outer end is preferably reduced at a^6 , and the extreme point of the outer end of each is preferably conical, as shown. These pistons are preferably made hollow for the sake of lightness, are closed at the inner end, and each is preferably provided with a drain-

age-passage for the escape of water, which is liable to accumulate.

A' represents a cylinder-head attached to one end of the casting A and containing 55 steam-ports a^7 , a^8 , &c., one for each cylinder.

A^2 is an annular exhaust-passage connected with the cylinders by exhaust-ports a^9 , a^{10} , &c., and a^{11} is an exhaust-pipe leading from said passage. 60

B is a steam-chest attached to the cylinder-casting A and having the live-steam inlet b.

C is a housing attached to the cylinder-casting A at the end of said casting opposite the one to which the cylinder-head is attached. 65

D is the main shaft of the engine. It passes through the housing C and cylinder-casting A and is supported and revolves in a bearing d , supported by the housing C, and a bearing d' , formed in the cylinder-casting A. Its inner end d^2 is preferably reduced in diameter, and the reduced portion passes through the cylinder-head A and preferably extends into the steam-chest B. 70

E represents a circular head rigidly secured to the shaft D. Its face e is inclined and contains an annular groove e' , within which a ring e^2 , having a concave face, preferably rests. Within the groove e' and resting upon the ring e^2 a series of rolls e^3 are arranged. 75

E' represents an antifriction-ring whose inner face preferably contains an annular groove e^4 , into which the rolls e^3 extend when said antifriction-ring is in place. The ring E' rests on an inwardly-extending shoulder e^5 of the head E, and a plate e^6 , attached to said head, preferably assists in keeping said ring in place. Against the back of the ring E' the inclined faces of the piston-points bear. 80

The back of the head E rests against an antifriction-ring e^6 , surrounding the shaft D. The face of this ring contains an annular concave groove e^7 , and it faces a similar ring e^8 , whose face contains an annular concave 95 groove e^9 and whose back rests against the inside of the housing C. Within the grooves e^7 and e^9 of the rings e^6 and e^8 a series of rolls e^{10} are arranged, and to the rim of the ring e^8 an inwardly-projecting band e^{11} is preferably attached, within which the ring e^9 is free to move. 100

To the inner end d^2 of the shaft D the hub F of a steam-valve F' is attached by means of a feather f, which, while causing said steam-valve to revolve with the shaft, permits it to move longitudinally thereon and seat firmly against the back of the cylinder-head.

The valve F' is preferably circular. It is preferably composed of a central circular portion f' , which alone preferably seats against the cylinder-head and a rim f^2 , whose inner edge is preferably raised above the outer face of the central portion f' of the valve. The central portion f' of this valve is pierced by a steam-port f^3 , preferably segmental in form, as shown, and long enough, exclusive of the part occupied by the cut-off valve-lip, hereinafter mentioned, to register with each of the cylinder-ports a^5 during as large a portion of the stroke of the piston in the cylinder with which the port connects as is ever necessary in practice.

The outer end of the hub F is preferably provided with a removable head f^4 . (Shown attached to the hub by means of a screw f^5 .) To this head f^4 a coiled spring f^6 , which surrounds the hub F, is attached. The inner end of this spring is attached to pinion g, which in turn is attached to a cut-off valve G, preferably segmental in shape. This valve rests against the face of the central portion f' of the steam-valve F' and moves between the hub F and the rim f^2 . Its forward edge is preferably provided with an inwardly-projecting flange g^4 , entering and extending across the main-valve port f^8 and preferably resting against the main-valve seat. It limits the movement of the cut-off valve and also prevents steam from passing back under the cut-off valve to a cylinder-port, with which the portion of the valve-port not covered by the cut-off valve has ceased to register.

The cut-off valve is operated by means of a governor attached to the steam-valve and revolving with it. This governor preferably consists of two segmental gears g^7 , pivotally attached to the steam-valve at opposite points g^2 , g^3 and meshing with said pinion g and each provided with a heavy arm or weight g^8 . When the shaft D revolves and the steam-valve is caused to revolve with it, centrifugal force tends to cause said arms g^8 to fly outward and, by communicating motion through the segment-gears g^7 to the pinion g, so move the cut-off valve G as to partially cut off the steam. This tendency is opposed by the coiled spring f^6 , attached to the steam-valve hub and the pinion attached to the cut-off valve which the governor-gears engage. The tendency of this spring is to cause the pinion to so revolve as to open the valve-port to the widest extent and at the same time draw the arms g^8 inward. By properly proportioning the weight of the arms g^8 and the strength and tension of the spring the speed of the engine may be kept constant and steam economized.

The valve and governor represented in Fig.

8 are the substantial equivalents of the cut-off valve and governor represented in the other figures. In the modification, H represents a circular cut-off valve which is provided with a steam-port h . h^1 , h^2 represent pins projecting from the face of the valve. H^1 , H^2 represent weighted arms pivotally attached to the steam-valve at opposite points h^3 , h^4 , and h^5 , h^6 inwardly-projecting arms rigidly attached to the arms H^1 , H^2 and having near the outer end of each a slot h^7 . These arms h^5 , h^6 are connected with the cut-off valve by means of the pins h^1 , h^2 , each of which extends into the slot of one of said arms. The weighted arms H^1 , H^2 are connected together by the coiled spring H^2 . The operation of this valve and governor is substantially the same as that of the preferred form.

The operation of my engine is as follows: Steam being admitted to the steam-chest passes through the steam-valve port and the cylinder port or ports which then register with the valve-port, and this produces a forward movement of the piston or pistons within the cylinders to which steam is thus admitted. The pistons forced forward press against the antifriction-ring E' and cause the head E beneath it and the shaft D to which said head is attached to revolve. It revolves with said shaft and its steam-port is thus brought into communication with the different cylinder-ports consecutively. If the speed increases beyond the desired point, the governor causes the cut-off valve to narrow the main-valve port, and in this way a uniform speed is maintained. As each piston in its turn reaches the upper part of the friction-ring it passes far enough forward to leave open the exhaust-port of its cylinder, and the steam behind it then escapes through such port and allows it to return to its original position, to which it is forced back by the continued motion of the head E. When so forced back, the piston closes the exhaust-port of its cylinder, and thus acts as a valve.

I have described forms of mechanism which I deem the best, but do not wish to have my claims confined thereto. I desire to cover all equivalents and to secure the underlying ideas broadly.

I claim—

1. In an engine the combination of a shaft; a head attached to the shaft having an inclined face; an annular groove in its face; a series of rolls in the groove; an antifriction-ring containing an annular groove within which said rolls extend, and back of said head and between it and a stationary rest a pair of grooved antifriction-rings surrounding said shaft and a series of rolls between said rings and resting in their grooves substantially as described.

2. In an engine a series of parallel stationary cylinders arranged around an axis and each having an exhaust-port; a piston in each cylinder; a revolute shaft; a head having an inclined face in front of said pistons, receiv-

ing pressure from the pistons and forced to revolve thereby; cylinder steam - ports; a main valve closing said ports having a steam-port through it, and connected with said shaft and revolved by it; cut-off valve on said main valve; governor-weights pivotally attached to the main valve, means for transmitting motion from one or both weights to the cut-off valve; and means tending to hold the cut-off valve open and opposing the outward movement of the governor-weights.

3. The combination in a steam-engine, of a main shaft; means causing it to rotate; a disk-valve pierced by a steam - port in the shape of a segment, connected with said main shaft; a segmental cut-off valve seated on the disk-valve; a spring connecting said valves and tending to hold said cut-off valve open; a pair of governor-weights; means pivotally connecting said weights to the main valve so as to cause them to be supported thereby and rotate therewith; and means connecting said weights to said cut-off valve, substantially as described.

4. In a steam-engine having a plurality of cylinders and steam-admission ports; a main-valve seat; a shaft; means causing the shaft to revolve when the engine is in motion; the main valve F' having a central circular part f' seated on said seat, and pierced by a segmental steam-port f³; a cut-off valve G, seated upon the face of the central part f' of the valve F', and having a flange g⁴ entering and

extending across the port f³ and resting against the main-valve seat; means connecting the valve F' to said shaft; and a governor operating said cut-off valve substantially as described.

5. In a steam-engine having a plurality of cylinders and steam-admission ports, a main-valve seat; a shaft; means causing the shaft to revolve when the engine is in motion; the main valve F' having a hub F, and a central circular part f', a rim f², surrounding the part f', and a segmental steam-port f³ through the part f', and, seating on said seat; means connecting said valve to said shaft, and causing it to rotate therewith; a segmental cut-off valve G having an inwardly-projecting flange g⁴ entering the valve-port f³, and which cut-off valve rests against the face of the main valve, and moves between the hub F and the rim f²; a pinion g surrounding said hub F and attached to the cut-off valve G; a coiled spring f⁶ connecting the main valve and the cut-off valve and tending to keep the cut-off valve open; and a governor operating said cut-off valve and consisting of two gears g', g', pivotally attached to the main valve at opposite points, g², g³, and meshing in with said pinion g, and each provided with a heavy outer arm g³ substantially as described.
